PORTABLE FOLDING IRONING BOARD

Beatrice Parker, Brooklyn, N. Y.

Application September 30, 1941, Serial No. 412,924

2 Claims. (Cl. 38—139)

This invention relates to new and useful improvements in ironing boards, and has particular reference to a portable folding ironing board.

The invention contemplates the construction of an ironing board as mentioned which is characterized by a pair of adjacent board sections and a hinge or hinges foldably connecting adjacent ends of these sections together.

The invention proposes to so locate the hinge or hinges on the sections of the ironing board that the sections may move from adjacent folded positions to aligned positions. In the latter position of the sections the board may be placed across chairs or other supporting elements and used in the usual way.

The invention further contemplates an arrangement by which the folded ironing board may be supported on a nail, clothes bar or other supporting element.

For further comprehension of this invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a portable folding ironing board constructed in accordance with this invention, looking upon it from the top.

Fig. 2 is a bottom view of the board shown in Fig. 1.

Fig. 3 is an elevational view of the board shown in Figs. 1 and 2 in its folded position, to which a supporting means has been applied.

Fig. 4 is a fragmentary enlarged elevational view looking in the direction of the line 4—4 of Fig. 3.

Fig. 5 is a fragmentary enlarged view similar to a portion of Fig. 3 but showing a modified supporting means.

Fig. 6 is another view similar to Fig. 5 but disclosing still another modified supporting means.

Fig. 7 is an enlarged vertical sectional view taken on the line 7—7 of Fig. 6.

Fig. 8 is a front elevational view of a folding ironing board provided with supporting means in accordance with another modification of the invention.

The portable folding ironing board, in accordance with this invention, includes a pair of adjacent board sections 10 and 11, and a hinge or hinges 12 hingedly connecting the adjacent ends of these sections. The hinges 12 are mounted on the bottom faces of the sections and are

of a construction which makes it possible for the sections to fold up adjacent each other as illustrated particularly in Figs. 3 and 4. Moreover, the hinges permit the sections to be opened to the position shown in Figs. 1 and 2, and then the adjacent ends of the section will contact each other forming shoulders which limit further pivoting. Thus the sections maintain aligned positions.

The board in the open position illustrated in Fig. 1 may be placed against two chairs, or a chair and table, or other supporting means, and act in the usual way.

Means is provided for hanging up the folded board, when this is desired. In the form of the invention shown in Figs. 3 and 4 this means comprises a loop of string or cord 14 which is engaged over one of the sections of the ironing board and moved to a position to extend across the hinges 12. The string 14 supports a hook 15 by which the ironing board may be suspended from a nail, clothes rod or other supporting member. When desired the loop 14 may be opened up and removed. The ends of the cord forming the loop 14 are shown tied together into a bow 16.

In Fig. 5 another modified form of the invention is disclosed in which a conventional wire clothes hanger 17 is shown extended across the hinges 12 of the folded board, to comprise the supporting means.

In Figs. 6 and 7 another modified form of the invention is disclosed in which means for hanging up the ironing board comprises a wire which has its ends 18a permanently attached to one of the leaves of the hinges 12, by welding, indicated by reference numeral 19, or the wire 18 may be attached to the leaves of the hinges in some other way. The wire 18 has a central upwardly extending portion 20. A hook 21 is slidably mounted on the wire 18. When the sections of the ironing board are in their folded positions, as shown in Figs. 6 and 7, the hook 21 projects above the top of the folded board and may be engaged upon a nail or other supporting member. When it is desired to open the ironing board so that it may be used for ironing, the hook 21 is merely slipped downwards on the wire 18 to one side or the other side of the central upwardly extending portion 20. In the latter position that hook 21 will be located beneath the adjacent edges of the sections 10 and 11 of the ironing board. Thus it will not interfere with the opening of the sections.

In Fig. 8 still another modified form of the invention has been disclosed in which the port-

able folding ironing board is shown disposed within an envelope 22 which has an opening and top flap 23 through which the board may be removed when desired. The envelope 22 is also provided with a tab 24 having an opening 25 by which it may be engaged on a nail or other supporting element.

It is to be understood that this device may be used, not only as an ironing board or clothes hanger, but also for any general purpose in the kitchen or elsewhere as a food slicing and chopping board, emergency table, etc. It also may be used as a protecting shield over the top of furniture for placing hot objects thereon.

This board may be made of any suitable material and also covered by the usual padding and removable cover. The board may be folded with the padding and cover when desired and placed or hung wherever desired.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A portable folding ironing board, comprising a pair of adjacent board sections, spaced hinges hingedly connecting adjacent ends of said board sections together, a hook arranged to project in an operative position from between the hinged ends of said board sections, and means attaching said hook to one of said board sections so that it may be moved from an operative

extended position to an inoperative position retracted between the adjacent faces of said board sections, comprising a length of wire disposed between said hinges and having its ends attached to the leaves of the hinges which are attached to one of said board sections, said wire being spaced from the adjacent edges of said board sections and having a central portion directed towards said adjacent edges, and means slidably attaching said hook to said wire to be movable to an operative position engaging said bent central portion and slidable to an inoperative position disengaged from said bent central portion.

2. A portable folding ironing board, comprising a pair of adjacent board sections, spaced hinges hingedly connecting adjacent ends of said board sections together, a hook arranged to project in an operative position from between the hinged ends of said board sections, and means attaching said hook to one of said board sections so that it may be moved from an operative extended position to an inoperative position retracted between the adjacent faces of said board sections, comprising a length of wire disposed between said hinges and having its ends attached to the leaves of the hinges which are attached to one of said board sections, said wire being spaced from the adjacent edges of said board sections and having a central portion directed towards said adjacent edges, and means slidably attaching said hook to said wire to be movable to an operative position engaging said bent central portion and slidable to an inoperative position disengaged from said bent central portion.

BEATRICE PARKER.
